J. H. REID

PROCESS OF PRODUCING NITROGEN CONTAINING COMPOUNDS

Filed Nov. 14, 1919

UNITED STATES PATENT OFFICE.

JAMES H. REID, OF PITTSBURGH, PENNSYLVANIA, ASSIGNOR TO INTERNATIONAL NITROGEN CO., OF CLEVELAND, OHIO, A CORPORATION OF DELAWARE.

PROCESS OF PRODUCING NITROGEN-CONTAINING COMPOUNDS.

Application filed November 14, 1919. Serial No. 338,109.

To all whom it may concern:

Be it known that I, JAMES H. REID, a citizen of the United States, residing at Pittsburgh, in the county of Allegheny and State of Pennsylvania, have invented a certain new and useful Improvement in Processes of Producing Nitrogen-Containing Compounds, of which the following is a full, clear, and exact description, reference being had to the accompanying drawings.

This invention relates to a process for the manufacture of nitrogen-containing compounds and more particularly to the production of such compounds from carbide subjected to nitrogen in the presence of heat. It is the general object of the invention to produce such compounds in a particularly efficient and economical manner.

Further and more limited objects of the invention will appear hereinafter and will be realized in and through the combinations of steps embodied in the claims annexed hereto.

In the drawings forming part hereof, there is shown an apparatus whereby the process may be realized in an effective manner. In said drawings, Fig. 1 represents a longitudinal sectional view through such apparatus; and Fig. 2 a sectional view corresponding to the line 2—2 of Fig. 1 and looking in the direction of the arrows.

Describing the parts by reference characters, 1 denotes generally a furnace made of suitable fire-resistant material. For convenience of description, the left-hand end 2 of the furnace shown in Fig. 1 is referred to as the "front" and the opposite end 3 as the "rear." Above the top of the furnace there is shown a charging bell 4 such as is employed with acetylene generators and blast furnaces. The bell is provided with a removable sealing cover 5 having an opening therethrough from which there extends a rod 6, forming an air-tight connection therewith, said rod carrying at its lower end a conical valve 7 cooperating with the lower frusto-conical end 8 of the hopper or bell. This valve stem or rod is shown as adjustable by being threaded into a collar 9 carried by spider arms 10 secured to the body of the bell or hopper. Extending down-

wardly from the lower end of the hopper is a pipe or conduit 11 which discharges into a horizontal heating chamber or retort 12 extending substantially from the front to the rear end of the furnace and communicating at its rear end with a similar chamber or retort 13, which in turn communicates at its front end with a similar chamber or retort 14. As many of these chambers may be employed as is desirable, depending upon the size of the furnace and the desired rate of production of the nitrified product. The rear end of the chamber 14 discharges through a vertical flue 15 into a closed receptacle 16, the flue being provided between said receptacle and the bottom wall of the furnace with a suitable valve 17 for sealing the said flue. The lower end of the flue 15 projects considerably below the top of the receptacle 16, for a purpose to be described hereinafter.

Extending longitudinally of each of the chambers 12, 13 and 14 is a shaft, the said shafts being indicated at 18, 19 and 20, respectively. The shafts extend through the ends of their respective chambers and are mounted in journals 21 provided on the front and rear walls of the furnace and are provided with driving means, such as pulleys 22 and 23, the shaft 19 having an additional pulley 24. The shaft 20 is provided with a pulley 25 shown as located at the front end thereof. The pulley 25 is adapted to receive power from any suitable power shaft (not shown) the power being transmitted through pulleys 25 and 23 and a belt 26 to the shaft 19 and by pulleys 22 and a belt 27 to shaft 18.

The chambers 12, 13 and 14 are circular in cross-section and each of the shafts is provided within its chamber with a screw feed conveyor, the said conveyors being indicated at 28, 29 and 30. The furnace 3 will be provided with any suitable means for heating the chambers 12, 13 and 14, a fluid burner 31 being indicated for this purpose.

Communicating with each of the retorts or chambers and preferably with the delivery end thereof, is a pipe indicated respectively at 32, each provided with a valve indicated at 32^a. Communicating with each

pipe 32 is a pipe 34 projecting thereinto. The pipes 32 serve to deliver nitrogen into each chamber or retort and the pipes 34 serve to deliver into each of the nitrogen pipes an agent capable of activating the combination of the nitrogen with the carbide. For this purpose, a finely divided nitrate may be employed. The nitrogen, being under a pressure of about 4 pounds per 10 square inch, will serve to exhaust such activating agent from the pipes 34 and to inject the same into the retorts or chambers.

In practising my process by an apparatus such as shown herein, I introduce into the 15 charging bell 4 finely ground carbide, as calcium carbide, having first displaced the air from the retorts or chambers by circulating nitrogen through the same by means of the pipes 32 and the outlet pipe 35. The carbide is fed through the retorts or chambers by means of the screw conveyors and is heated to about 650° C. in the atmosphere of nitrogen therein. At this stage, the valves 32^a and 35^a will be opened and adjusted so 20 as to supply to each of the retorts or chambers nitrogen under a pressure of about 4 pounds to the square inch. The valves (not shown) in the pipes 34 being opened, the nitrogen will inject the activating agent into 25 each retort and the carbides therein will be subjected to the action of the nitrogen and the activating agent suspended therein.

A great advantage in injecting the activating agent with the nitrogen resides in the saving of time required for the nitrification of the carbide and the efficiency of the operation. As is well known, the combining of nitrogen with carbide is an exothermic reaction, the 30 heat evolved being sufficient to raise the temperature of the mass about 75° C.

By blowing in the activating agent with the free nitrogen I obtain at once a rise in temperature of the mass in each retort and a 35 quick combination of the nitrogen with the carbide by reason of the strong and virile condition of the activating agent, which is used while at its highest point of efficiency. Where an activating agent is mingled with the carbide and introduced therewith into 40 the retorts, it will have become weakened to the extent to which it has combined with the carbide before coming under the influence of the free nitrogen and the nitrification proceeds much more slowly than where 45 such agent is mingled with the nitrogen and introduced therewith.

Both the quickness and the completeness of the combination of nitrogen with the carbide are facilitated by subjecting the material to be nitrified to mixtures of nitrogen with the activating agent applied successively to the said material during its transit through the zone of heat; also by the progressive heating of the material as 50 it travels from the top of the retort as-

sembly to the bottom of such assembly, where the source of heat is located.

Having thus described my invention, what I claim is:

1. The process of producing a nitrified product which consists in conducting the material to be nitrified through a progressively heated zone and subjecting the carbide in such zone to an atmosphere of nitrogen having an activating agent mingled therewith.

2. The process of producing a nitrified product which consists in conducting the material to be nitrified through a progressively heated zone containing a mixture of an activating agent with nitrogen under super-atmospheric pressure.

3. The process of producing a nitrified product which comprises feeding the material to be nitrified through a zone of heat and subjecting the heated carbide while in transit to the action of mixtures of nitrogen with an activating agent applied successively thereto.

4. The process of producing a nitrified product which comprises feeding the material to be nitrified through a zone of heat and subjecting it while in transit to the action of mixture of nitrogen with activating agent applied successively thereto.

5. The process of producing a nitrified product which consists in continuously feeding an agitated mass of the material to be nitrified through a zone of heat and subjecting such heated mass to the action of successively applied mixtures of nitrogen, under super-atmospheric pressure, with an activating agent.

6. The process of producing a nitrified product which consists in conducting the material to be nitrified through a zone of heat, subjecting the heated material to the successive action of mixtures of nitrogen, under super-atmospheric pressure, with an activating agent, and agitating the mass while in transit through such zone.

7. The process of producing a nitrified product which consists in subjecting a heated mass of material to be nitrified to the action of a mixture of nitrogen and an activating agent supplied to the said material, and agitating the said material during the operation.

8. The process of producing a nitrified product which consists in conducting the material to be nitrified along a progressively heated retort and subjecting the said material to the action of a mixture of nitrogen and an activating agent supplied thereto while in transit.

9. The process of producing a nitrified product which consists in conducting an agitated mass of the material to be nitrified through a heated retort and subjecting the same while in transit to the action of a mix-

ture of nitrogen and an activating agent supplied to the retort adjacent to the delivery end thereof.

10. The process of producing a nitrified product which consists in conducting an agitated mass of the material to be nitrified through a heated retort and supplying to said mass, adjacent to the delivery end of

said retort, a mixture of nitrogen and an activating agent directed into said retort ¹⁰ in opposition to the movement of said material therealong.

In testimony whereof, I hereunto affix my signature.

JAMES H. REID.
